IMPACT SCREW DRIVER

Jesse C. McCorkhill, Xenia, Ohio

Application August 9, 1944, Serial No. 548,729

1 Claim. (Cl. 145—53)

1

This invention relates to a tool and more particularly to a tool adapted to translate linear impacts into rotary or torque impacts.

In certain industries and trades it is necessary to remove screws, nuts, bolts, rivets and other fastening devices that have become set in position. For example, in airplanes screws are used in assembling metallic parts. In the event the parts become damaged, or for some other reason must be removed, difficulty has been experienced in loosening the screws, for the reason that the screws may have rusted or corroded, so as to be impossible of removal by the use of a manually operated screw driver or other tool used in unscrewing the screws.

An object of this invention is to provide a tool wherein the tool may be struck or hit by a hammer or other impact providing device in a direction parallel to the longitudinal axis of the tool and the longitudinal axis of the screw, which tool translates the linear impact movement into a rotary or torque impelling movement, so as to utilize the linear movement in forcing an adapter or implement into engagement with the work to be actuated and utilizing the rotary or torque impelling movement to rotate the work.

Another object of this invention is to provide a hammer driven tool for actuating fastening devices, illustrative of which are screw threaded members wherein a linear impact movement is used in forcing the implement into engagement with the fastening device and a rotary or torque movement is used in actuating the fastening device, such as screw threaded parts, which tool is easily produced, easily handled, efficient and dependable and at the same time inexpensive.

Other objects and advantages reside in the construction of parts, the combination thereof and the mode of operation, which will become more apparent from the following description.

Referring to the drawings,

Figure 1 discloses a side elevational view of the tool.

Figure 2 is a longitudinal sectional view taken substantially on the line 2—2 of Figure 1.

Figure 3 is an end view of the tool with the adapter removed.

Figure 4 discloses a longitudinal cross sectional view of a modification.

In the drawings, the reference character 10 indicates a tubular main body portion or handle sleeve member of the implement. It is provided with a knurled hand-grip portion surrounding the periphery of the handle. The lower end tapers at 10a. The handle 10 is provided with a centrally located bore 10b having spiral splines or threads 10c. The upper end of the main body portion 10 is provided with an enlarged recess or cavity 10d, terminating in a shoulder 10e. A

2

threaded aperture 10f is located near the end of the handle and extends radially.

The internal threads or splines 10c engage a spirally grooved implement supporting member or spirally spined spindle 12, having a reduced portion 14 projecting outwardly from the handle 10, which reduced portion is preferably square in cross sectional area and is provided with a recess receiving a ball 16, spring urged outwardly by a small helical spring 18 and adapted to engage and lock a work engaging implement 20, shown in dotted lines. This work engaging implement may be a screw driver, a socket wrench or any other type of implement adapted to engage the work.

The upper end of the tool supporting member 12 is reduced at 12a and projects into the enlarged recess or cavity 10d. A suitable retaining ring or spring 22 is seated in a groove of the reduced portion 12a and engages a washer 24, seated against the shoulder 10e. The washer 24 is mounted for movement with the implement supporting member 12.

A compression spring 26 is mounted between the washer 24 and a capping member 28, provided with a reduced portion 28a projecting into the recess 10d and locked in position by a suitable set screw 30, engaging the threads of the aperture 10f. The capping member 28 constitutes the impact receiving portion of the tool.

A suitable oil retaining member 32 is mounted in the tapering portion 10a of the handle 10 and surrounds the implement supporting member 12, so as to oil the implement supporting member. The implement supporting member 12, and the parts carried thereby, are always biased outwardly by the compression spring 26, which incidentally, in moving the implement supporting member outwardly into the position shown in Figure 2, rotates the implement supporting member 12, together with the adapter carried thereby.

The direction of the threads on the implement supporting member 12 is selected either to loosen a screw or to tighten a screw. The pitch of the grooves, splines or threads is so selected that a reciprocatory or linear impact applied to an impact receiving head of the tool in a direction parallel to the longitudinal axis of the spindle translates the linear impact movement into a rotary or torque impelling movement. The threads or grooves and the projections extending into the grooves must be of sufficient dimension and length to withstand hammering blows applied to the impact receiving head or capping member 28.

When the tool is to be used, a suitable adapter is selected. If a screw is to be loosened, a screw loosening implement is selected. If, for example, a screw having a kerf is to be removed, an adapter simulating a screw driver is selected and mounted on the end of the implement support,

ing member or spindle 12. The operator grips the handle 10 with one hand, seating the work engaging portion of the adapter in position upon the work. With the other hand the operator may hammer the head 28 applying the blows parallel to the longitudinal axis of the tool, so as to cause the adapter to move towards the work. Instead of a manual hammer being used, any other suitable hammering device or tool may be used, such as a pneumatic hammer or an electromagnetic hammer. Due to the spiral arrangement of the groove in the spindle 12 the linear impact applied to the implement is translated into a rotary or torque impact, tending to rotate the work. This jars loose the screw, if it is to be loosened, or whatever the work may be. If it is to be tightened, the impact may be used in tightening the parts. After each hammer blow, in the absence of external forces, the head and hammer impact receiving member is restored to the position shown in Figure 2. It may be that the operator may bias the handle towards the work, thereby causing the adapter to firmly engage the work in readiness for the linear impact that is being translated into rotary impact.

This tool has been found very effective in removing screws from wings of airplanes that have been damaged and is used to remove screws that cannot be removed manually with the aid of conventional screw drivers. The adapter is selected for the particular work. In the event it is a screw to be loosened and the head of the screw is provided with a kerf, a straight edge screw driver is used. In the event the screw is provided with cross grooves, an adapter fitting into the cross grooves is selected. In the event the head of the screw is provided with a square or a hexagon recess, an adapter is selected that will fit such a recess. If the head of the screw is square or hexagonal, a socket adapter may be selected. Likewise, if nuts are to be removed, sockets engaging the nuts are selected.

In the modification disclosed in Figure 4, the tubular sleeve handle member 60 is provided with an internally threaded bore 62 receiving a threaded spindle 64 adapted to support a work engaging adapter. The spindle is urged into the position shown in Figure 4 by a compression spring 66 seated against a washer 68 held in fixed relation with respect to the end of the spindle by a screw 70. The spring 66 and the washer 68 are mounted in an enlarged recess 72. The outer end of the recess is threaded and receives a threaded head or capping member 74, held in position by a suitable set screw 76 seated in a threaded aperture in the handle member 60. The lower end of the handle is provided with a reduced cylindrical portion 78, provided with a longitudinally extending key seat 80, receiving a suitable detent 82 in a sleeve or ferrule 84 of member 86 held upon the end of the spindle 64 by a screw 88, extending into a circumferential groove 90 in the spindle 64. A collar portion 92, either integral with, press-fitted upon or fixedly secured to the spindle 64, engages member 86, so as to cause member 86 to move longitudinally with respect to the handle 60. Member 86 is prevented from rotating with the spindle by virtue of the detent 82 being seated in the key seat 80, so that member 86 may reciprocate on the handle 60 without rotating with the spindle. Member 86 is mounted for non-rotary movement with respect to the handle and is mounted for non-axial movement with respect to the spindle.

In the device disclosed in the drawings, the parts have been shown as metallic parts cooperating to translate reciprocatory movement into rotary movement. Instead of using a metallic sleeve provided with spiral grooves, a rubber insert could be mounted between the spiral spindle and the tubular sleeve, the rubber insert being vulcanized to the metallic sleeve and thereby provide a resilient or yieldable impact translating device.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claim.

Having thus described my invention, I claim:

In a device for actuating a screw member or other turnable fastening means, the combination including a tubular member having an internal bore provided with spiral grooves, said bore terminating in an enlarged portion terminating in a threaded portion, a spindle member provided with spiral portions seated in the spiral grooves of the tubular member, means fixedly attached to the spindle member and including a washer seated in the enlarged portion of the cylindrical bore, a hammer-engaging capping member threadedly engaging the threads of the tubular member, a compression spring positioned between the capping member and the washer for urging the spindle member into extended position, the spindle member projecting beyond the tubular member, the portion of the spindle member projecting beyond the tubular member being provided with an annular groove, a ferrule terminating in a tubular flange rotatably mounted on the spindle member near the end of the spindle member, the flange telescopically engaging the tubular member, means for preventing rotation of the ferrule relative to said tubular member, means extending from the ferrule into the annular groove for preventing longitudinal movement of the spindle member with respect to the ferrule without rotation thereof, and a collar fixedly attached to the spindle member beyond the ferrule, the tubular member cooperating with the spindle to translate longitudinal impacts by a hammer applied to the capping member into rotary impulses applied to the screw member or other fastening means.
